UNITED STATES PATENT OFFICE.

WARREN C. GLEASON AND JAMES C. RYAN, OF CHICAGO, ILLINOIS.

DESIGN FOR A HOSE-CARRIAGE BODY.

SPECIFICATION forming part of Design No. 19,315, dated September 17, 1889.

Application filed May 22, 1889. Serial No. 311,741. Term of patent 7 years.

To all whom it may concern:

Be it known that we, WARREN C. GLEASON and JAMES C. RYAN, citizens of the United States, and residents of Chicago, county of Cook, and State of Illinois, have invented a new and original Design for a Hose-Carriage Body, of which the following is a specification.

In the accompanying drawing, forming a part of this specification, the figure is a perspective representation of a hose-carriage body, showing the front and side.

The leading features of our design consist in the arch K, terminating under the seat in a curve F, and the arch paneled, as at E, on its face, and the panels separated by scrolls H beneath the end of the seat and round the curve F.

The minor features of our design consist in

the scroll ornaments I, the four large double segment-lines and four small double segment-lines on the head of the hose-reel, and in the scroll panels P beneath the seat and the configurations on the end of the box below the seat, the same being inclined and rectangular lines with leaves above and scroll ornaments between.

What we claim is—

A design for a hose-carriage body herein described, and shown by the accompanying drawing.

WARREN C. GLEASON.
JAMES C. RYAN.
